COMBINED HEATER HOUSING FOR HAIR CURLERS AND VANITY MIRRORS

Arne Bybjerg Pedersen, Kalunborg, Denmark, assignor,
by mesne assignments, to Bristol-Myers Company, New
York, N.Y., a corporation of Delaware

Filed Nov. 27, 1968, Ser. No. 14,693

Claims priority, application Denmark June 26, 1968

Term of patent 14 years

Int. Cl. D28—03

U.S. Cl. D86—10

FIG. 1 illustrates a perspective top view of the combined heater housing for hair curlers and vanity mirrors;

FIG. 2 illustrates a bottom perspective view of the combined heater housing for hair curlers and vanity mirrors of FIG. 1; and

FIG. 3 illustrates a perspective view of the heater housing of FIG. 1 in an open position.

I claim:

The ornamental design for a combined heater housing for hair curlers and vanity mirrors, as shown.
